UNITED STATES PATENT OFFICE.

GEORGE M. STEVENSON, OF BALTIMORE, MARYLAND.

DOUBLE-SEAMING MACHINE.

Application filed April 27, 1921. Serial No. 464,951.

To all whom it may concern:

Be it known that I, GEORGE M. STEVENSON, a citizen of the United States, residing at Baltimore, in the county of Baltimore and State of Maryland, have invented certain new and useful Improvements in Double-Seaming Machines, of which the following is a specification.

This invention relates to machines for making cans and particularly to mechanism for securing the head or cover to a can body by means of a double seam.

Briefly stated the invention comprises a continuously operable chuck carrier carrying a plurality of rotatable chucks, means for pressing can bodies on said chucks and a rotating disk carrying a plurality of pairs of curling and finishing rollers adapted to act successively upon the can bodies to secure the heads or covers thereon by a double seam.

In the following detailed description I shall refer to the accompanying drawings, in which—Figure 1 is a longitudinal vertical sectional view on the line 1—1 of Fig. 2, showing a machine embodying my invention; Fig. 2 is a transverse vertical sectional view on the line 2—2 of Fig. 1; Figs. 3 to 8 inclusive, are diagrammatic views, illustrating the successive positions assumed by the curling and finishing rollers during a single operation of the machine; Fig. 9 is a transverse vertical sectional view on the line 9—9 of Fig. 1; and Figs. 10 and 11 are detail sectional views showing respectively the seam as produced by the curling roller and as finished by the finishing or closing roller.

The power shaft 10 is journaled in the end frame members 15, 16 and driven by any suitable source of power connected to the pulley 11. The main shaft 12 is connected to the power shaft through gears 13 and 14. A small gear 17, splined on the shaft 12, engages a pinion 18, loosely mounted on a stub shaft 19, secured to the frame member 15, the pinion being in mesh with an interior gear ring 20, projecting laterally from a gear wheel 21, which is loosely mounted upon shaft 12. A wheel-shaped chuck carrier 23 having a hub 22 loosely mounted on shaft 12, carries a series of tubular bearings 24 in which are journaled shafts 25 carrying the chucks 26 at one end and at the other

end provided with pinions 27 which are rotated by meshing with the exterior peripheral teeth on the gear wheel 21.

A seaming disk 28, splined to shaft 12, carries near its periphery a series of pairs of laterally projecting stub shafts 29, upon which are mounted the complementary curling rollers 30 and finishing or closing rollers 31.

A disk 32, formed integral with the end frame member 16, is provided in its periphery with a barrel cam slot 33, in which are positioned rollers 34, carried by hubs 35, the latter being slidably mounted in sockets carried by a disk member 38, rotatably mounted on shaft 12 and provided with peripheral teeth 39 meshing with a pinion 40, splined to shaft 10. Can shaping and holding heads 37 are carried on the ends of spindles 36, which are loosely mounted in the hubs 35. The heads 37 have conical front face portions which enter and accurately center the can bodies and also serve to spread the bodies into proper cylindrical form in case they have been accidentally distorted. The hubs 35 and the sockets in the disk member 38 are angular in section to prevent the hubs from turning while permitting a free longitudinal movement effected by the rollers 34 in the cam groove 33.

The disk member is formed with a lateral extension 38^a provided with a series of sockets or receptacles 43 to receive the can bodies 42, the sockets having lateral lug extensions 42^a to support the can heads 51. Clamping or forming dogs 44 are pivotally attached to the can carrier 43 and are normally held out of contact with the can bodies by means of coiled springs 45 which are held between lugs and heels 46 on the inner ends of the dogs. A cam 48 carried on the outer end of arm 47, engages the dogs successively and forces them inwardly into contact with the periphery of the cans.

The chuck carrier 23 is rotated upon the shaft 12 by the engagement of the pinion 50, splined to the power shaft 10, with the teeth 49 on the periphery of the carrier.

The can bodies and can heads are fed to the machine at the position indicated in Fig. 2 by the line *a*—*b* and the headed cans 50 are discharged at the position indicated by the line *c*—*d*. The can bodies are received by the sockets 43, while the heads rest upon

the extension lugs 42^a. The chuck carrier 23 and disk member 38, which carries the holding head plates 37 rotate together at the same speed, being driven from the power 5 shaft 10 by the same size pinions 40 and 50. As each can body 42 approaches the uppermost position, the corresponding holding plate 37 is moved inwardly by its roller 34 following the cam groove 33, in the stationary disk 32. The can body is thus pushed by the holding plate 37 firmly against its can head 51; the latter being pushed and tightly held against its revolving chuck 26. These operations take place just prior to 10 the engagement of the clamping dog 44 with the cam 48 which pushes it down upon the revolving can body for the purpose of truing the body in case it has become distorted or misshapen. I have found that the 15 dogs may be omitted as the can bodies are usually well formed and any slight deformation is overcome by the engagement of the holding plate 37 at one end and the curling and finishing rollers at the other.

20 As shown in Figure 9, in the operation of the machine, it is necessary that the sets of curbing and finishing rollers 30 and 31 be so spaced that there will be seven sets thereof for cooperation with the eight can holding chucks. When the can body reaches the 25 uppermost position on the vertical axis, the curling roller 30 of the nearest pair comes into engagement with the peripheral bead on the can head, as indicated diagrammatically in Fig. 4. The roller continues in engagement with the can body while the latter is moving a little more than 45° in its orbit. The disk 28 moves slightly faster than the chuck carrier 23 and disk 38, advancing 30 45° in one complete revolution. Consequently during the 45° period that the roller 30 travels in engagement with the can from position Fig. 4, to position Fig. 5, it presses inwardly against the can and then 35 gradually recedes. During this operation the bead on the can top or cover 51 and the outwardly flaring edge of the can body are gradually forced into the peripheral groove on the roller 30 which causes said bead and can margin to be coiled or curled in the 40 manner indicated in Fig. 10. When said can has moved to the position indicated in Fig. 6, 45° below the horizontal axis, the curling roller 30 has separated from the can and the corresponding finishing roller 31 is 45 approaching it. By the time said can has nearly reached the lower vertical axis the said roller 31 has overtaken it, as indicated in Fig. 7, and by engagement with its 50 groove, flattens said previously curled bead in the manner indicated in Fig. 11, so that when the finishing roller moves away from the can at 45° from the lower vertical axis as indicated in Fig. 8, the can head is 55 surely fastened to the can body by means of

a double seam which stands up in a flattened bead. The can is then discharged into a suitable delivery chute.

I claim:

1. A machine of the character described, comprising a chuck carrier, chucks carried thereby, a disk, curling and finishing rollers rotatably mounted on said disk, and means for revolving the chuck carrier and disk in the same direction at different speeds. 70

2. A machine of the character described, comprising a chuck carrier, chucks carried thereby, means for rotating the chucks on the carrier, a disk, curling and finishing rollers rotatably mounted on said disk, and means 80 for revolving the chuck carrier and disk in the same direction, but at different speeds. 75

3. A machine of the character described comprising a main shaft, a chuck carrier loosely mounted on said shaft, a disk on and rotatable with the shaft, curling and finishing rolls rotatably mounted on the disk, and means for rotating the chuck carrier at a speed differing from that of the shaft and the roller carrying disk but in the same direction. 85

4. A machine of the character described, comprising a main shaft, a chuck carrier loosely mounted on said shaft, a disk on and rotatable with the shaft, curling and finishing rolls on the disk, and means for rotating the chuck-carrier at a speed differing from that of the shaft and the roller carrying disk, disk-like member rotatable on the shaft, and can body shaping and holding 100 heads on said disk-like member opposite the chucks. 95

5. A machine of the character described, comprising a main shaft, a chuck-carrier loosely mounted on said shaft, a disk on and rotatable with the shaft, curling and finishing rolls on the disk, means for rotating the chuck-carrier at a speed differing from that of the shaft and the roller carrying disk, a disk-like member rotatable on the shaft, and can body shaping and holding heads on said disk-like member opposite the chucks, said holding heads being movable toward and from the chucks and independently rotatable therewith. 105 110

6. A machine of the character described comprising a main shaft, a chuck-carrier loosely mounted on said shaft, a disk on and rotatable with the shaft, curling and finishing rolls on the disk, means for rotating the chuck-carrier at a speed differing from that of the shaft and the roller carrying disk, a disk-like member rotatable on the shaft, and can body shaping and holding heads on said disk-like member opposite the chucks, said holding heads being movable toward and from the chucks and independently rotatable therewith, and carrying can body seats, the can bodies being held in such seats by clamping dogs. 115 120 125 130

7. A machine of the character described comprising a drive shaft, a main shaft directly geared thereto, a disk splined on the main shaft, curling and finishing rollers independently rotatable on said disk, a chuck carrier loosely mounted on the main shaft, and having gear teeth, a pinion on the drive

shaft meshing with said teeth, rotatable chucks carried by the chuck carrier and gearing from the main shaft for independently rotating the chucks in the carrier. 10

In testimony whereof I affix my signature.

GEORGE M. STEVENSON.
